UNITED STATES PATENT OFFICE

155,179

DESIGN FOR A DUAL HANDLE CONTROL

Erwin J. Panish, Bridgeport, Conn.

Application January 4, 1949, Serial No. 39

Term of patent 14 years

(Cl. D26—5)

To all whom it may concern:

Be it known that I, Erwin J. Panish, a citizen of the United States, residing at Bridgeport, county of Fairfield, and State of Connecticut, have invented a new, original, and ornamental Design for a Dual Handle Control, of which the following is a specification, reference being had to the accompanying drawing, forming part thereof.

Figure 1 is a perspective view of a dual handle control showing my new design.

Fig. 2 is a front elevational view of the control, and

Fig. 3 is a side elevational view of the control.

I claim:

The ornamental design for a dual handle control, as shown.

ERWIN J. PANISH.
